UNITED STATES PATENT OFFICE.

JOHN T. DETTERER, OF WILLSHIRE, OHIO.

BEDSTEAD.

SPECIFICATION forming part of Letters Patent No. 275,894, dated April 17, 1883.

Application filed March 3, 1883. (No model.)

To all whom it may concern:

Be it known that I, JOHN T. DETTERER, a citizen of the United States, residing at Willshire, in the county of Van Wert and State of Ohio, have invented certain new and useful 5 Improvements in Bedsteads; and I do hereby declare the following to be a full, clear, and exact description of the invention, such as will enable others skilled in the art to which it app- 10 pertains to make and use the same, reference being had to the accompanying drawings, and to letters or figures of reference marked thereon, which form a part of this specification.

My invention relates to improvements in 15 the construction of bedsteads, and in the combination therewith of springs and slats for supporting the bedding.

It has for its object to so construct the several parts of the bedstead as to adapt them for 20 ready connection and disconnection.

The invention has also for its object to avoid 25 the expense, and more especially the inconvenience, resulting from the use of slat-rails, and a series of independent slats in combination therewith, all as fully described herein- 30 after, and as shown in the accompanying drawings, in which—

Figure 1 is a plan view, Fig. 2 a side elevation, and Fig. 3 a longitudinal vertical section, of my improved bedstead. Fig. 4 is a perspective view of the head-board of a bedstead, showing one part of the fastening devices; Fig. 35 5, a like view of part of one of the side rails of the bedstead, showing the other part of the said fastening devices. Fig. 6 shows in perspective the two parts of the fastening devices. Fig. 7 shows a modified construction thereof by a like view, and Fig. 8 shows in perspective the construction and relative arrangement 40 of the springs and slats.

Like letters of reference indicate like parts in the above figures of drawings.

H indicates the head-board, and F the foot- 45 board, the uprights or posts *h* of which are provided with hook-fastenings A, composed of a plate, *a*, and a slotted or forked hook, *a'*. Hooks B, of like construction, are attached to the head and foot boards, or their lower or cross rails, *h' f'*, a short distance from the side rails, R, for 50 purposes hereinafter described.

The side rails, R R, of the bedstead are provided with T-shaped couplings C C, formed on rectangular supporting-plates *cc*. These hook-couplings A B C may be constructed as shown in Figs. 1 to 6; or they may be constructed as 55 shown in Fig. 7, where the supporting-plates *a c* are respectively provided with a rib, *a' c'*—that is to say, the plate itself may be formed T-shaped, the ribs *a' c'* being let into mortises formed in the posts and rails, and said rib, as 60 well as the angular flange on the coupling C, may also be dispensed with, and the coupling simply screwed to the end faces of the rails R, as will be readily understood. In this manner I provide a simple means for coupling the head 65 and foot boards with the side rails.

In bedsteads of usual construction the side rails, R R, are provided with slat rails or racks for the purpose of supporting the slats equidistant from each other. This construction 70 not only entails additional expenses in material and labor, but is a source of considerable annoyance, on the ground that the slats, if not made of well-seasoned wood and accurately fitted, cannot be readily removed, or replaced 75 when removed, and are liable to fall out of their recesses at any time, while such a slat-rail is an excellent harbor for vermin. Another inconvenience in bedsteads of this construction lies in the fact that the slats have to be 80 placed in position or removed therefrom one by one.

This invention is designed to overcome these inconveniences and difficulties by dispensing with the slat-rails altogether on the one hand, 85 and on the other hand by connecting all the slats of a bedstead flexibly and equidistant from each other, so that they may be rolled into a bundle and removed bodily and unrolled and replaced. The advantages of such a 90 structure are apparent, and do not only affect the handling of the bed-slats, but also their storage and transportation, as none of the slats can become detached from the others when bundled, or become mixed with those of another bedstead.

This invention is also designed to dispense with the usual bed-springs or spring-mattresses by making the slats sufficiently yielding or springy. 100

As shown in the drawings, the slats S are connected together by means of flexible connections, such as leather, rubber, a textile fabric, or metal. The attachment of these flexible strips or ribbons D may be effected in any suitable or desirable manner, either by tacking or screwing the same to the face of the slats, or by mortising the slat and passing the flexible strip through the mortise, and securing it therein by means of one or more rivets, d, or by means of tacks, screws, or other like fastening.

Instead of supporting the flexibly-connected slats rigidly from a slat-rail, I support them from two strong flat metal (preferably steel) springs, E, terminating at both ends in T-heads e, that are hooked upon the hooks B, thus imparting to the slats a considerable degree of flexibility or elasticity, sufficiently so for general purposes as to adapt the bedstead for use without the usual spring-mattresses. To hold the slats in proper position the springs E are provided with abutments or shoulders e', against which the end slats are laid, and thus hold the series of slats in proper position.

It will be understood that I do not wish to limit myself to the use of spring-supports for the connected slats, as such slats may be used with great convenience in bedsteads of usual construction.

Having thus fully described my invention, what I claim as new is—

1. In a bedstead, the combination, with the head and foot boards provided with forked coupling-hooks A, of the side rails provided

with T-couplings C, substantially as described, and constructed for operation as set forth.

2. In a bedstead, the supporting-slats connected together by means of flexible connections, substantially as and for the purposes 40 specified.

3. In a bedstead, the combination, with supporting-slats, of longitudinal spring-supports extending from the head to the foot board, as described, for the purpose specified. 45

4. In a bedstead, a series of flexibly-connected slats, in combination with supporting-springs provided with abutments for the end slats of the series, substantially as described, for the purposes specified. 50

5. In a bedstead, the combination, with the head and foot boards, of the longitudinal springs E, detachably connected therewith, substantially as and for the purposes specified.

6. In a bedstead, the combination, with the head and foot boards, the springs E, and their abutments e', detachably connected with said head and foot boards, of a series of flexibly-connected slats, substantially as described, for the purposes specified. 60

7. In a bedstead, the combination, with the head and foot boards and their forked hooks B, of the T-ended springs E, their abutments e', and a series of flexibly-connected slats, substantially as and for the purposes set forth. 65

In testimony whereof I affix my signature in presence of two witnesses.

Witnesses: JOHN T. DETTERER.
